GRATE MAGNET

Maurice D. Woodruff, Springfield, Ohio, assignor to The Bauer Bros. Company, Springfield, Ohio, a corporation of Ohio

Application December 28, 1949, Serial No. 135,398

13 Claims. (Cl. 209—223)

This invention relates to magnetic separators, and more particularly to those used to remove metal particles from grain, coffee, peanuts and the like, in a processing or handling step of such materials.

Heretofore these separators have been placed in the floor of a chute or like part of a conveying system in such wise that the grain or other material passes over the separator with entrained metal particles adhering to the separator and being deposited thereon. It is proposed by the instant invention to introduce a new conception in separating methods, wherein the material is constrained to pass through a grate type separator in close proximity to the magnets, which separator may be conveniently mounted in a hopper for gravity feed of the material to the magnet.

The object of the invention is to simplify the construction as well as the means and mode of operation of grate type separators as disclosed herein, whereby such separators may not only be economically manufactured, but will be more efficient and satisfactory in use, adaptable to a wide variety of applications and be unlikely to get out of repair.

A further object of the invention, which is concerned with the grate magnet as a new article of manufacture, is to expose the flowing material more effectively to magnetic attraction.

Another object of the invention is to obtain effective magnetic attraction without imposing any material restriction to flow through the magnet.

A further object of the invention is to utilize a plurality of magnets, arranged in rows, to induce alternate polarity in intersecting members which, with the rows of magnets, make up the grate structure.

Still another object of the invention is to obviate the possibility of metal particles failing to be intercepted by the magnet because of descent midway between the intersecting members or pole pieces.

A still further object of the invention is to provide deflecting means in accordance with the preceding object without, however, restricting flow to and through the magnet.

A further object of the invention is to provide a separator possessing the advantageous structural features, the inherent meritorious characteristics and the mode of operation herein mentioned.

With the above primary and other incidental objects in view as will more fully appear in the specification, the invention intended to be protected by Letters Patent consists of the features of construction, the parts and combinations thereof, and the mode of operation, as herein-after described or illustrated in the accompanying drawings, or their equivalents.

Referring to the accompanying drawing, wherein is found the preferred but obviously not necessarily the only form of embodiment of the invention,

Fig. 1 is a view of the magnet, with deflecting means, in top plan;

2

Fig. 2 is a view in side elevation, partly broken away, and

Fig. 3 is a view in end elevation, partly broken away.

Like parts are indicated by similar characters of reference throughout the several views.

Referring to the drawing, a separator in accordance with the instant invention has a grate-like construction, it being adapted for installation in the lower part of a hopper so that the material containing separable matter is constrained to pass through the separator as it discharges from the hopper. The structure comprises a plurality of spaced apart rows of magnets 11, the several rows of magnets being intersected by transverse spaced apart metal strips 12. Together, the magnets 11 and strips 12 provide a plurality of magnetic elements which define a grate presenting a plurality of openings 13 for passage of the material therethrough.

The magnets 11 are preferably elongated in shape, and, in each row, are mounted in end to end alternately opposed relationship with like poles of adjacent magnets in facing relation. There is a metal strip 12 at each end of the rows of magnets and other strips 12 received between adjacent pairs of magnets. The like poles of adjacent magnets are thus separated by and abut a strip 12, each such strip being common to and extending across the several rows of magnets. The several strips 12 thus assume the character of pole pieces of alternate polarity, and are spaced apart a distance equal to the length of one magnet 11. The distance between the rows of magnets also being approximately equal to the length of one magnet, the openings 13 are substantially square or equal sided.

Each magnet 11 has a longitudinal opening 14 therethrough (Fig. 2) which, with the magnets aligned in a row, cooperates to define a longitudinal passage to receive a tie bolt 15. Corresponding openings in the pole pieces 12 permit passage of the bolts 15 therethrough, the opposite ends of the bolts projecting through and beyond the end pieces 12 and receiving nuts 16. Tightening of the nuts 16 upon the bolts effects a clamping engagement between the magnets 11 and pieces 12, joining the parts into a unitary rigid structure. The magnets 11 are of such shape, or so positioned upon the tie bolts 15, that the upper surfaces thereof will extend generally downward in the direction of travel of the material, thereby reducing turbulence in the material flow and avoiding the formation of lands upon which material might collect.

By reason of their intimate association with and relation to the magnets 11, the pole pieces 12 acquire an induced magnetism and form with the magnets 11 a plurality of magnetic elements. Accordingly, metal particles entrained in the material will be attracted to one or another of the magnetic boundaries as the material passes through an opening, such particles being thus separated from the material which continues on through the grate.

Deflector means are associated with the grate structure to preclude the possibility of a metal particle descending through an opening 13 at a point where it will be equally attracted by the opposite pole pieces and associated magnets and hence not be deposited on any. This means is in the form of an assembly of small diameter round rods or wires 17 extending across the openings 13 centrally thereof and in transverse relation to the rows of magnets 11. The rods 17 are supported by side plates 18 of non-magnetic material, arranged alongside the outer rows of magnets 11 and in embracing relation to the ends of the pieces 12 to which the plates are structurally connected. Being supported in elevated relation to the grate the rods 17 are sufficiently far removed from the magnetic field that they are not substantially affected thereby whether they be of magnetic or non-magnetic material. So that there may be no ap-

preciable restriction to flow the rods are positioned so that the diagonal distance between each rod and an adjacent pole piece is approximately equal to the distance between the pieces.

Accordingly, metal particles tending to descend midway between opposite pole pieces 12 of the openings 13 are deflected by the rods 17 into the magnetic field of one or another of such pieces.

Supplemental deflecting plates 19 may be secured to the separating unit to insure that all material will pass through the separator rather than around the edges thereof intermediate the separator and the material discharge duct in which the separator is positioned.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect.

Having thus described my invention, I claim:

1. A grid type magnetic separator, including a plurality of spaced apart rows of magnets, the magnets of each row being arranged in alternately opposed relationship with like poles of adjacent magnets in facing relation, metal strips having the character of pole pieces extending transversely across the several rows of magnets to acquire an induced magnetism, there being a strip at each end of the rows of magnets and one between the opposing faces of each pair of magnets, and means for clamping the magnets and transverse strips into a unitary assembly to define a grate structure.

2. A grid type magnetic separator according to claim 1, characterized in that said clamping means is in the form of a plurality of tie rods, one for each row of magnets, each extending longitudinally through a respective row of magnets and associated transverse strips.

3. A grid type magnetic separator, including a plurality of spaced apart rows of magnets and a plurality of spaced apart metallic strips having induced magnetism extending across the several rows, the magnets of each row being in alternately opposed relationship with like poles of adjacent magnets in facing relation and said strips being interposed between the opposing faces of adjacent magnets to assume the character of pole pieces.

4. A grid type magnetic separator, including a plurality of spaced apart rows of magnets, the magnets of each row being arranged in alternately opposed relationship with like poles of adjacent magnets in facing relation, metal strips extending transversely across said rows of magnets and received between opposing pairs of magnets in each row to be inductively magnetized thereby, other transverse strips at the opposite ends of the rows of magnets, tie rods extending between said other strips and passed longitudinally through the rows of magnets and interposed strips, said magnets being arranged on said tie rods to present downwardly sloping surfaces to the material passed through the separator.

5. A grid type magnetic separator, including a plurality of spaced apart rows of magnets and a plurality of spaced apart metallic strips extending across the several rows at right angles thereto, there being strips at the ends of said rows and other strips intermediate adjacent pairs of magnets, the magnets of each row being arranged in alternately opposed relationship with like poles of adjacent magnets in facing relation and receiving said

other strips therebetween, and means for uniting said magnets and strips into an assembly defining a grate structure presenting a plurality of material passing openings each bounded by magnets and by strips of induced magnetism and alternate polarity.

6. A grid type magnetic separator, including a plurality of spaced apart rows of magnets, the magnets of each row being located in alternately opposed relation to one another, a plurality of spaced apart metallic strips so arranged with respect to the magnets to be inductively magnetized thereby and extending at right angles to the magnets across the several rows, said magnets and said strips cooperating to define a grate structure presenting a plurality of rows of material passing openings, and deflecting means common to respective rows openings for precluding passage of material through said openings centrally thereof at points of equalized magnetic attraction.

7. A grid type magnetic separator, including a plurality of spaced apart rows of magnets and a plurality of spaced apart metallic strips of induced magnetism at right angles to said magnets and extending across the several rows thereof, the magnets of each row being in alternately opposed relationship with like poles of adjacent magnets in facing relation and said strips being interposed between the opposing faces of adjacent magnets to assume the character of pole pieces of alternating polarity, said magnets and strips cooperating to define a grate structure presenting a plurality of material passing openings having magnetic boundaries, and deflecting means overlying said openings to preclude the passage of material therethrough at points where the magnetic attraction of said boundaries is equalized.

8. A grid type magnetic separator, including a plurality of spaced apart rows of magnets, the magnets of each row being arranged in alternately opposed relationship with like poles of adjacent magnets in facing relation, metal strips extending transversely across the several rows of magnets at the opposite ends thereof and other metal strips extending in spaced apart relation to each other and to the first strips transversely across the rows of magnets, the first said strips abutting the ends of the rows of magnets and said other strips being received between the opposing faces of adjacent pairs of magnets, said strips acquiring from said magnets an induced magnetism of alternate polarity, means interconnecting said magnets and strips to define a grate structure presenting a plurality of material passing openings having magnetic boundaries, a series of small diameter non-magnetic deflector rods extending in overlying relation to said openings to deflect metallic matter tending to pass centrally through the openings toward one or another of the magnetic boundaries, and means for fixing said deflector rods with respect to the grate structure.

9. A grid type magnetic separator according to claim 8, characterized in that said last named means comprises non-magnetic side plates at the ends of said metal strips and parallel to the rows of magnets, said deflector rods being supported between said plates in transverse relation to the rows of magnets and in intermediate vertically spaced relation to said metal strips.

10. A grid type magnetic separator according to claim 8, characterized in that the diagonal distances between each deflector rod and the metal strips on either side thereof is approximately equal to the distance between said strips.

11. A grid formed of a plurality of spaced magnetic bars, spacers extending between the bars to form a grid, said spacers being aligned in rows transversely of the bars, said spacers being permanent magnets, the arrangement being such that the ends of magnets engaging each bar is of the same polarity.

12. A magnetic separator grate comprising a non-magnetic substantially rectangular frame, a series of magnetic parallel cross bars including two terminal bars

positioned in said frame in spaced relationship, said terminal bars located adjacent said frame and extending along opposite sides thereof, permanent magnets located intermediate said magnetic parallel cross bars in contact therewith in such manner that like poles of adjacent magnets lie next to and on opposite sides of each of said cross bars.

13. A magnetic separator grate comprising a plurality of spaced magnetic parallel bars, permanent magnets located intermediate said spaced magnetic parallel bars in such manner that like poles of adjacent magnets lie in contacting relation with and on opposite sides of each of said magnetic bars.
